UNITED STATES PATENT OFFICE.

WILLIAM B. GOODE, OF PHILADELPHIA, PENNSYLVANIA.

PENCIL-CLIP.

971,190.

Specification of Letters Patent. Patented Sept. 27, 1910.

Application filed May 25, 1909. Serial No. 498,211.

To all whom it may concern:

Be it known that I, WILLIAM B. GOODE, citizen of the United States, residing at Philadelphia, in the county of Philadelphia and State of Pennsylvania, have invented 5 certain new and useful Improvements in Pencil-Clips, of which the following is a specification.

This invention comprehends certain new 10 and useful improvements in pencil clips or retainers, and the invention has for its primary object a simple construction of device of this character which may be very cheaply and easily manufactured, and which will be 15 efficient in operation so that when applied to a pencil, it may securely hold the same in a vest pocket or the like.

With these and other objects in view as 20 will more fully appear as the description proceeds, the invention consists in certain constructions, arrangements and combinations of the parts that I shall hereinafter fully describe and claim.

For a full understanding of the invention, 25 reference is to be had to the following description and accompanying drawings in which:

Figure 1 is a perspective view of my improved clip holder, showing the same applied to a pencil; Fig. 2 is a similar view of 30 the device detached; Fig. 3 is a transverse sectional view of that form of the device which is illustrated in Figs. 1 and 2. Fig. 4 is a view illustrating one application of 35 the device to a pocket.

Corresponding and like parts are referred to in the following description and accompanying drawings by the same reference characters.

40 My improved pencil clip is constructed of a single piece of wire embodying two longitudinal bars 1 and 2 connected at their ends as shown to form two end cross bars 3 and 4, the device also embodying an intermediate cross bar 5. In this form of the invention, the wire is bent to form the different parts as shown, one end of the wire constituting a portion of the longitudinal bar 2 and being looped around the angularly 45 disposed intermediate cross bar 5 as indicated at 6, the said cross bar being transversely curved as shown and looped at its

extremity around the longitudinal bar 1 as indicated at 7. In the preferred arrangement of parts in this embodiment of the invention, the end cross bars 3 and 4 are turned back slightly or offset as shown, and in the normal unflexed position of the parts the looped end 6 of the wire is offset from the plane of the other parts so as to yield in 60 a backward direction, the loop 6 sliding on the inner cross bar 5 so as to accommodate the device to pencils of different diameters.

From the foregoing description in connection with the accompanying drawing, it 65 is believed that the operation of my improved pencil clip or retainer is obvious. In the practical application of the device, the pencil is slipped downwardly through the offset cross bars 3 and 4 or back of the 70 intermediate cross bar 5, the device being thereby securely held upon the pencil and the two longitudinal bars 1 and 2, together with their lower cross bar 4 constituting a clip member which may extend downwardly 75 along the outside of a vest pocket or the like so as to securely retain the pencil in the user's pocket, the outwardly offset lower ends of the bars 1 and 2 facilitating the operation of the attaching of the device to the 80 pocket.

Having thus described the invention, what is claimed as new is:

As a new article of manufacture, the herein described clip consisting of a single piece 85 of wire bent to form longitudinal bars and connecting end bars, one end of the wire being bent transversely intermediate of the ends of the longitudinal bars and looped around one of them, the other extremity of 90 the wire constituting a portion of the other bar, and looped around the intermediate cross bar, the normal position of the loop of the last named extremity in the unflexed condition of the same being at a point between the ends of the transversely bent intermediate portion of wire, as and for the purpose set forth.

In testimony whereof I affix my signature in presence of two witnesses.

WILLIAM B. GOODE. [L.S.]
